UNITED STATES PATENT OFFICE.

AUGUSTINE DAVIS, JR., OF CINCINNATI, OHIO.

WELDED TANK.

Application filed January 22, 1927. Serial No. 162,703.

This invention relates to an improved welded construction for compartment tanks of tank trucks, the object being to provide a partition construction of maximum strength 5 to resist the severe strains, including the surge of the liquid against the partition heads, to which such tanks are subjected. The object is likewise to permit of the use of comparatively light gauge metal without 10 danger of breakage or leakage, the lightening of the dead weight that must be transported being an important consideration. The object is, further, to secure these advantages while retaining the advantages, hitherto obtained by a different construction of less 15 inherent strength, of double partitions, each forming the closed end of its compartment, with the liquid-retaining welds outside welds so that if any leak should occur at these 20 welds it can be observed and readily repaired. Still another object is to provide in a novel and advantageous manner for compensating for localized expansion or contraction occasioned by the welding of the 25 connection between the compartments. Another feature of preferred construction consists in the provision of separate finish bands, each covering one of the two pairs of welds, the advantage of which will become 30 apparent.

In the accompanying drawings forming part hereof:

Fig. 1 is a side elevation of a compartment tank showing the partition construction between two compartments, with portions of the finish bands broken away and in section, the tank being broken out at opposite sides of the partition in order to contract the showing of the tank within the width 40 of the sheet;

Fig. 2 is a longitudinal sectional view on a larger scale of the partition construction, the tank being broken out longitudinally in order to economize space; and

Figs. 3 and 4 are views similar to Fig. 2, showing modifications.

For simplicity Fig. 1 may be considered to represent a vehicle tank of two compartments 2, 2, though it will be understood that these tanks commonly consist of three or more compartments, and that the partition construction will occur at as many junctions 50 between compartments as there may be.

The tubular shells of the compartments 55 are marked 3, 3, and the partition heads are marked 4, 4.

My Patent 1,311,155 of July 29, 1919, covers a construction which has been highly successful in practice, and the advantages of which are retained in the present invention, 60 plus the advantage of greater strength for given weight, or more practically stated, very ample strength with more lightness. In that patent it will be observed that the spaced apart partition heads are inserted 65 into the adjacent ends of the shells, head wall first, with the flanges extending toward each other, these flanges being welded to the shells and their edges being bent outward and welded together. The patent shows the 70 diaphragm walls of the heads straight, but for greater strength it has been the practice to form them with a dish, that is to say, concavo-convex, the bulge of the dish for necessary reasons being away from the 75 flange, or in other words inwardly of the liquid-holding compartment.

In the present invention the disposition of the compartment heads is reversed, and their flanges 5, 5 are inserted edge first into 80 the adjacent ends of the shells 3, 3, the heads themselves protruding from the shells, with their bulges outward from the interiors of the compartments. The flanges 5, 5 need be inserted only a comparatively short distance into the shells, to which the flanges are united by continuous, fluid-tight 85 welds 6, 6 joining the edges of the shells to the outer sides of the flanges. The complete liquid-tight compartments are then connected together by a connecting band 7, which overlaps the portions of the flanges 5 projecting from the shells beyond the welds 6, and by welds 8, 8 which unite the edges of 90 the band 7 to the outer sides of the head flanges. The welds 8 do not retain the liquid contents of the compartments and need not necessarily be liquid-tight. The welds 6 which do retain the liquid are outside welds 95 and are readily accessible.

The connecting band 7 is preferably formed with one or more beads, bends or crimps 9 intermediate the welds 8 to compensate for strains set up in welding. This bead may be outwardly directed, as in Figs. 1 and 2, or inwardly, as in Fig. 3, or it may be omitted entirely as in Fig. 4.

In order to cover the welds, while rendering them readily accessible, two finish bands 10 are provided, each band of a width to 110 embrace a pair of welds 6, 8. These bands may be tacked in place by welding as indi-

cated at 11, or held in place mechanically, or both.

Fig. 4 illustrates the fact that a single wide finish band 10° may be used to cover all four welds, as well as the connecting band, but the use of separate bands has the advantage that a supply of finish bands all of the same size will serve irrespective of the spacing between the shells in different jobs. In this connection it may be stated that the distance between the heads at the circumference will necessarily vary according to the diameter of the tank and the amount of dish in the heads. The heads need not be spaced at the circumference more widely than is compelled by the approach of their convexities at the center, where it is preferable that there be a slight distance between.

20 A telltale drip-pipe 12 is welded into the bottom of the connecting band 7 to give indication in the unlikely event of there being any leakage into the space between the compartments.

25 While certain embodiments of the invention have been illustrated, it will be understood that other arrangements may be used without departing from the essential novelty.

I claim:

30 1. In a welded compartment tank, the combination with the shells of two tank compartments, of flanged partition heads having their flanges set edge first part way into the adjacent ends of said shells and welded thereto, with the heads themselves protruding toward each other, and a connecting band overlapping and welded to the flanges of both heads where they protrude from the shells.

40 2. In a welded compartment tank, the

combination with the shells of two tank compartments, of flanged partition heads having their flanges set edge first part way into the adjacent ends of said shells and welded thereto, with the heads themselves protruding toward each other, and a connecting band overlapping and welded to the flanges of both heads where they protrude from the shells, said connecting band containing means for taking up localized expansion and 50 contraction.

3. In a welded compartment tank, the combination with the shells of two tank compartments, of flanged partition heads having their flanges set edge first part way into 55 the adjacent ends of said shells and welded thereto, with the heads themselves protruding toward each other, and a connecting band overlapping and welded to the flanges of both heads where they protrude from the 60 shells, and two separate finish bands, each encircling one pair of welds between a head, its shell and the adjoining end of the connecting band.

4. A welded partition construction between the liquid-holding compartments of a multiple-compartment welded tank, comprising the shells, protruding partition heads set flange first into the adjacent ends of the shells and welded thereto, and means uniting 70 the compartments thus formed.

5. A welded partition construction between the liquid-holding compartments of a multiple-compartment welded tank, comprising the shells, protruding partition heads 75 set flange first into the adjacent ends of the shells and welded thereto, and a connecting band welded to and uniting the compartments thus formed.

AUGUSTINE DAVIS, JR.
